UNITED STATES PATENT OFFICE.

CLIFFORD DUDLEY BABCOCK, OF NEW YORK, N. Y.

ANTENNA FOR WIRELESS-TELEGRAPH SYSTEMS.

No. 919,115.

Specification of Letters Patent. Patented April 20, 1909.

Application filed January 24, 1906. Serial No. 297,559.

To all whom it may concern:

Be it known that I, CLIFFORD D. BABCOCK, a citizen of the United States, and a resident of New York, in the county of New 5 York and State of New York, have invented a new and useful Improvement in Antennæ for Wireless-Telegraph Systems, of which the following is a specification.

My invention relates to transmitting and 10 receiving antennæ for wireless telegraph systems.

The object of my invention is to provide antennæ which are peculiarly adapted for use on shipboard, but which may be employed in connection with land stations 15 also, and which involve certain novel features which render them particularly efficient.

In the drawings which accompany and 20 form a part of this specification I have illustrated diagrammatically two embodiments of my invention although it is to be understood that I do not limit myself to the particular arrangements illustrated inasmuch 25 as many modifications may be made therein without departing from the spirit of my invention.

In the drawings, Figure 1 represents a transmitting or receiving antenna which 30 may be an open-end or a loop antenna, and Fig. 2 represents a transmitting or receiving loop antenna.

In Fig. 1, A A' represent the masts of a ship which support the antenna wires B B, 35 C C. The approximately vertical portion of the antenna consists of any desired number of wires B B, the lower ends of which enter the apparatus house and the upper ends of which are attached to and separated by the spreader D. The spreader D is connected to the rope or cable E, which passes over a pulley on the mast and the lower end of which may be secured to the cleat G when the antenna has been hoisted 40 in position. A strain insulator F may be connected in said rope or cable if desired. The approximately horizontal portion of the antenna consists of a corresponding number of wires C C, the outer ends of 45 which are secured to and separated by the member H, which is attached to the mast A' by the members I I consisting of tarred ropes or hard rubber or other insulators. The member H may be made of metal, in

which case the two sides of the antenna are 55 closed by said member H to form a loop antenna. The planes of the wires B B and of the wires C C are both vertical. By thus locating the approximately horizontal portion of the antenna in a vertical plane, 60 a number of advantages are secured, some of which are that there is less swinging back and forth, and up and down than would be the case if the spreaders D and H were horizontal; the whole antenna lies 65 within the plane of the masts; each of the horizontal wires when used for receiving will be cut by different portions of the lines of force of the advancing waves, if said wires are broadside on to their source and 70 I have found that the distances over which signals may be received are therefore greater than when said wires are in a horizontal plane.

In Fig. 2, the wires B C B', which constitute the antenna are maintained in a vertical plane and at a considerable angle to each other, as shown. The spreaders D, D to which the wires are secured and by which they are separated are attached to the 80 ropes or cables E E which pass over pulleys on the masts and which may be secured to suitable cleats when the antenna has been hoisted into position.

The antenna shown in Fig. 2 is a loop 85 antenna, the detailed arrangements of which with respect to the other circuits of the system have been set forth in Patent No. 806,966 granted to Lee de Forest. The advantage of employing the horizontal wires 90 C in Figs. 1 and 2 and the second set of wires B' in Fig. 2, is that thereby the total length of the antenna is increased so that its natural period, and the wave length corresponding thereto, is made greater than 95 that of a vertical antenna having its height equal to the height of those of the type shown in said figures. This feature is especially valuable on shipboard where the height of the mast and the guying space is limited. 100 The longer wave lengths obtainable by the arrangement herein described are desirable because thereby greater distances may be covered. The form of antenna shown in Fig. 2 is especially efficient because it 105 encloses the maximum area of space with masts of given height and separation, and different portions of the loop are each in distinct

portions of the field of force of the waves to be received and therefore the amount of energy absorbed therefrom is a maximum.

I claim:

- 5 1. A wireless telegraph antenna comprising an approximately vertical portion and an approximately horizontal portion, said portions being formed by the same continuous wires, and the said horizontal portion consisting of a plurality of parallel conductors disposed in a substantially vertical plane, substantially as described.
- 10 2. A wireless telegraph antenna comprising an approximately vertical portion consisting of a plurality of substantially parallel wires all disposed in the same plane, and an approximately horizontal portion formed by an extension of said wires, and consisting of a plurality of substantially parallel conductors all disposed in the same plane as said vertical wires, substantially as described.
- 15 3. A wireless telegraph antenna, comprising an approximately horizontal portion forming a loop and consisting of a plurality of conductors suitably spaced apart and disposed in a vertical plane; and each conductor having a downward extension lying in the same plane as the horizontal portion, substantially as described.
- 20 4. A wireless telegraph antenna, comprising an approximately horizontal loop and an

approximately vertical loop extending at a considerable angle to each other, and each loop composed of a plurality of parallel conductors all disposed in the same vertical plane, substantially as described.

5. A wireless telegraph antenna comprising an approximately horizontal loop composed of a plurality of parallel conductors disposed in a vertical plane, and an approximately vertical loop extending from one end of said horizontal loop, and composed of a plurality of vertical conductors disposed in the same vertical plane as said horizontal conductors, substantially as described.

6. A wireless telegraph antenna comprising an approximately horizontal loop composed of a plurality of parallel conductors disposed in a vertical plane, and a pair of approximately vertical loops extending from the ends of said horizontal loop and each composed of a plurality of vertical conductors disposed in the same vertical plane as said horizontal conductors, substantially as described.

In testimony whereof, I have hereunto subscribed my name this 19th day of Jan. 1906.

CLIFFORD DUDLEY BABCOCK.
